UNITED STATES PATENT OFFICE.

JAMES E. GROSJEAN, OF LIMA, OHIO, ASSIGNOR, BY DIRECT AND MESNE ASSIGNMENTS, OF ONE-FOURTH TO LEON F. MONTGOMERY, OF FORT RECOVERY, OHIO, AND ONE-FOURTH TO FRANK L. MAIRE, OF LIMA, OHIO.

SOLE FOR BOOTS AND SHOES.

1,297,834.

Specification of Letters Patent. Patented Mar. 18, 1919.

Application filed June 26, 1918. Serial No. 242,074.

To all whom it may concern:

Be it known that I, JAMES E. GROSJEAN, a citizen of the United States, residing at Lima, in the county of Allen and State of Ohio, have invented new and useful Improvements in Soles for Boots or Shoes, of which the following is a specification.

This invention relates to improvements in composite soles for boots or shoes of that 10 general type, as described in my pending application, Serial No. 234,710, which is characterized by a reinforced flexible base and a tread portion of rubber and fibrous material vulcanized together and secured by vulcanization to said base.

The objects of the invention are to facilitate and lessen the cost of manufacture of soles of the type referred to, to enhance their flexibility, to provide for the use of a minimum quantity of rubber and to provide increased strength and superior wearing properties.

By the term "sole" I refer to the whole sole or to any part thereof with which a 25 tread portion of the general character stated may be incorporated, whether such tread portion extend over the whole sole or over the heel or over the sole in the ordinary or narrow sense of the term, *i. e.* the half sole 30 or the forward portion of the whole sole which provides support for the ball of the foot and the toes.

With the stated objects in view the invention consists in certain features of structure 35 and organization which will be set forth in detail as the description proceeds.

An embodiment of the invention is illustrated in the accompanying drawing, where- 40 in:

Figure 1 is a bottom plan view of a sole in which the features of the invention are incorporated, the same being shown in the course of manufacture.

Fig. 2 is a central vertical sectional view 45 thereof.

Fig. 3 is a bottom plan view of the sole as completed and ready for use.

Figs. 4 and 5 are detailed longitudinal 50 and cross sectional views showing a modified or alternative construction.

Similar characters of reference designate corresponding parts throughout the several views.

The salient parts of the sole are a substan-

tially flat base or backing 1 whose material 55 is strong yet readily flexible and a tread portion 2 which is secured to the base 1. As shown the tread portion 2 is located in the forward portion of the whole sole but it may be extended throughout the whole sole or it 60 may be located or duplicated in the heel.

According to the invention the base 1 consists of two relatively thin sheets or layers 3 of rubber placed face to face in originally adherent relation and independent strands 65 4 of fibrous material, *e. g.* somewhat stout cord or twine arranged between and pressed into the rubber layers 3. The strands 4 are disposed in spaced parallel relation at somewhat close intervals, are preferably located 70 transversely of the tread portion and are drawn or stretched between said layers whereby they will be without slack. As thus constructed the flexibility of the base is enhanced while at the same time it is strength- 75 ened by the strands 4 whereby it can not stretch or widen in the direction of the sole in which said strands are disposed. In the preferred construction the upper layer of the base is somewhat thicker than the lower 80 layer, the latter being a comparatively thin sheet whose principal function is to hold the strands 4 in the desired spaced parallel relation to one another.

The base having the features of structure and relation above described, may be conveniently and economically manufactured by cutting the same from a sheet formed by a rolling operation in which the layers 3 with the strands 4 interposed 90 between them and held under tension are pressed together.

The tread portion 2 includes regularly arranged fibrous strands which are presented endwise to the tread surface. As 95 shown and preferred the tread portion is composed of juxtaposed transverse units whose cross sectional structure is similar to the cross sectional structure of the base 1, that is to say the transverse units, which are 100 originally in adherent relation, each consist of relatively thin layers 6 of rubber, generally similar in relation to the layers 3 of the base, and independent strands of fibrous material 7, *e. g.* cord or twine ar- 105 ranged in substantially parallel relation between the rubber layers, the strands 7 being presented endwise to the tread surface

and being somewhat heavy and coarse whereby they provide a multiplicity of stout, very closely associated fibrous plugs, the rubber of the tread portion being merely sufficient to hold the plugs in place and to give the tread portion a finished surface and edge and suitable cushioning properties.

In course of manufacture the tread portion may be initially secured to the base 1, adjacent its underface, in any suitable manner, but preferably by suitable cement or adhesive material. In case the tread portion occupies only a part of the area of the whole sole the latter is built up to suitable thickness, preferably to the thickness of the tread portion by the application throughout the rest of its area of a member 8, which, like the tread portion, may be initially secured to the base 1 by suitable cement or adhesive material. Where, as shown, the tread portion 2 is located in the forward portion of the whole sole, the member 8 conforms to the shank and heel portions of said sole. Said member may be composed entirely of rubber or it may be composed of rubber having fibrous material incorporated therein in any suitable way and arrangement.

30 The sole is preferably completed by a marginal supporting strip 9 of rubber which may, or may not, have fibrous material incorporated therewith, the tread portion 2 being arranged within said strip whose inner edge adjoins and conforms in outline to the edge of said tread portion. As preferred, the base 1 has a marginal projecting portion 10 of suitable width upon which the strip 9 is laid. As regards the construction shown, the combined area of the tread portion 2 and the member 8 is less than the area of the base 1 whereby said tread portion and member may be so arranged on said base that the latter will have a projecting portion which constitutes the aforesaid marginal portion 10 and preferably entirely circumscribes the tread portion 2 and member 8; and the marginal supporting strip 9 is laid on the marginal portion 10 in the same plane as the tread portion 2 and member 8, said strip being co-extensive with said marginal portion and initially secured in any suitable manner, preferably by suitable cement or adhesive material. The strip 9 may be continuous or it may be formed in juxtaposed complementary sections.

60 The finished sole, as shown in Fig. 3, is vulcanized throughout, the pressure employed preferably being exceptionally heavy and the vulcanization effecting the most secure and permanent union of the adjacent parts. Thus the rubber or equivalent material of the tread portion is united with 65 the utmost security to the fibrous material

of the tread portion, the tread portion as an entirety is similarly united to the base 1 whose layers 3 and strands 4 are permanently bonded together, the supporting strip 9, if employed as preferred, is similarly united both to the base 1 and tread portion 2, having a homogeneous union with the rubber or equivalent material of said tread portion and base, and the member 8, if employed, is similarly united to the tread portion, the base 1 and the supporting strip 9. 70 75

If desired, but merely as a measure adopted out of an abundance of precaution, the base, subsequent to the vulcanization of the sole, may be connected by stitching 11 to 80 the above described parts bonded thereto, the stitching being preferably provided in parallel rows, one of which is located within the supporting strip 9 and the other of which is located within the tread portion 2. 85

In some cases it may be desired or preferred to reinforce the base longitudinally as well as transversely and where such longitudinal reinforcement may be advantageous it will also be desirable to provide 90 a base of somewhat heavier construction. Thus, as shown in Figs. 4 and 5, the base is composed of two sheets 1^a and 1^b laid one on the other and each similar to the base 1 above described as regards the arrangement of the parallel independent strands or fibrous material between the layers of rubber. In the sheet 1^a the parallel fibrous strands, as 4^a, are disposed transversely of the sole as in the base 1 of the 100 embodiment described but in the companion sheet 1^b the parallel fibrous strands, as 4^b, are disposed longitudinally of the sole and at approximate right angles to the strands 4^a.

Either sheet may be arranged uppermost but it is preferred to arrange the sheet 1^a uppermost and to arrange the sheet 1^b adjacent the tread portion. The sheets 1^a and 1^b are in originally adherent relation and when the sole is vulcanized in the manner described each sheet is vulcanized throughout and is also vulcanized to the other. The base as thus constructed will not have the enhanced flexibility of the base 1 but it will have a sensible degree of flexibility and will also have great strength. 110 115

In both forms the principles of construction are the same and the same manufacturing advantages are realized.

Having fully described my invention, I 120 claim:

1. A composite sole for boots or shoes having a base composed of layers of rubber arranged face to face and parallel independent strands of fibrous material disposed 125 at somewhat close intervals and stretched tightly between the layers of rubber and a composite tread portion secured to said base, said sole being vulcanized throughout.
2. A composite sole for boots or shoes 130

having a base composed of layers of rubber arranged face to face and parallel independent strands of fibrous material disposed transversely at somewhat close intervals and 5 stretched tightly between the layers of rubber and a composite tread portion secured to said base and composed of transverse units, each consisting of layers of rubber and parallel independent strands of fibrous 10 material disposed between said layers of rubber and presented endwise to the tread surface, said sole being vulcanized throughout.

3. A composite sole for boots or shoes 15 having a base composed of companion sheets laid one on the other and each consisting of layers of rubber arranged face to face

and parallel independent strands of fibrous material disposed at somewhat close intervals and stretched tightly between the layers of rubber, the strands of one sheet being disposed transversely of the sole and the strands of the other sheet being disposed longitudinally of the sole, and a composite tread portion secured to said base, said sole being 20 vulcanized throughout.

In testimony whereof I have hereunto set my hand in presence of two subscribing witnesses.

JAMES E. GROSJEAN.
